LIQUID LEVEL GAUGE

Georg Saruchanoff, Berlin-Charlottenburg,
GermanyApplication June 3, 1938, Serial No. 211,618
In Germany March 24, 1937

10 Claims. (Cl. 73—302)

1

This invention relates to improvements in measuring instruments for ascertaining the weight of a liquid stored in containers such as gasoline tanks.

In my father's U. S. specification No. 2,033,153 an instrument of this kind is described by means of which the weight of the liquid is ascertained by measuring the hydrostatic pressure of the liquid with the aid of a U-shaped pipe filled with mercury, one leg of said pipe communicating with the liquid in the tank and the other with a line of compressed air. A zero-adjusting device permits of adjusting the mercury level in each case of measuring.

In an improved modification of this apparatus described in my German Patent No. 654,350, the zero-adjusting device is adjusted by means of an electrode firmly attached to the U-pipe in combination with a displacer, the zero-adjusting device being adjusted to zero-position by hand, whereas the adjustment of the full hydrostatic pressure in regard to the zero-position (above zero) is automatically effected by means of the stationary electrode.

Now the object of the present invention is to adjust automatically also the zero-adjusting device to zero-position, so that the apparatus except the manipulation governed by an optic and an acoustic signal of a switch and a cock is entirely operated automatically. According to the invention, for this purpose, all valves for introducing into or withdrawing from the U-pipe the liquid to be weighed and the air under pressure are automatically adjusted, for instance, by opening or closing the valves by means of a single electric switch. All the valves are constructed as is well-known in the form of electrovalves which are opened or closed by an electric current so that they are closed or opened respectively when the current is interrupted.

The automatic adjustment of the zero-adjusting device to zero-position on the one hand and of the full hydrostatic pressure in the tank to this zero-position on the other hand especially affords the essential advantage of a greater exactness of measuring, because this adjustment is quite independent of the sight and manipulations of the operator whereby different adjustments of the same zero-position—unavoidable when adjusting by hand—appear as excluded. Furthermore hereby an increased safety in working the measuring device and an extraordinary simplification of its use and manipulation are obtained, as the whole measuring operation can be carried out, for instance, by one single switch,

2

after the cock, controlling the inflow of the mercury from the displacer into the U-pipe or the reflex into the displacer, has been opened and subsequently closed, preferably by hand.

The measuring device according to the invention is preferably constructed in such a manner that the liquid-controlling valves of the U-pipe for controlling the adjustment of the zero-adjusting device to the zero-level of the tank and the compressed-air valve of the displacer form an electric circuit to be closed by the switch, that the valve for admitting the compressed air to the displacer and the electrode in the right-hand leg of the U-pipe form a second circuit to be closed by rising mercury, that the valves for admitting the tank liquid and the compressed air under the full hydrostatic pressure of the tank form a third electric circuit (to be closed in another position) with the compressed air outlet valves closed in this moment, and that when setting the switch into a third position the valve for admitting the tank liquid is opened and the compressed air outlet valve is opened and is automatically closed under the full hydrostatic pressure as soon as the zero-position of the zero-adjusting device is attained. A further feature of my invention consists therein that the mercury contained in the displacing device is automatically displaced towards the U-pipe and shut off for adjusting the zero-position whereas in my previous modification the displacement was effected by a differential piston or a flexible diaphragm adjusted by hand whereby in accuracies in adjusting the zero-adjusting device to the standard level N—N might be entailed.

Furthermore in order to prevent the mercury from passing for any reason whatever out of the U-pipe into the compressed air line, instead of the check valve provided for in the device of Patent No. 2,033,153, according to this invention a contact is inserted into the circuit of the electrovalve controlling the admission of the tank liquid to the U-pipe. Said contact being secured to the left-hand leg of the U-pipe opens the circuits of the electrovalve when the mercury in the left-hand leg falls beneath said contact, whereby the further inflow of the tank liquid into the U-pipe is automatically shut off.

In the drawing an example of the measuring device according to the invention is diagrammatically illustrated.

Near the bottom of the tank 1 the pipe 2 is arranged which is provided with a shutting-off slide (not shown) and a hand-operated control valve 3 to be able to control the flow of the tank

liquid from the tank into the U-pipe 6 when the slide is in open position. Behind the control valve 3 an electro-valve 4 is provided for the purpose of increasing safety in working the measuring device. This electrovalve is inserted into an electric circuit in such a manner that the opening of the valve and the flow of the tank liquid from the tank into the U-pipe can only take place by adjusting the change-over switch 36, i. e. only while the measuring is done by the operator. Furthermore in the circuit of the electrovalve 4 the contact 32 in the lower left-hand leg of the U-pipe is inserted in such a manner that when the mercury falls below the contact 32 the circuit is interrupted or disconnected, whereby the valve 4 is closed and the passing of mercury into the compressed air line 19 is prevented which could take place by inadvertence of the operator, for instance, by suddenly opening the control valve 3. A socket 8 connects the left hand leg 6 of the U-pipe with the electrovalves 7 and 4. The outlet 5 of valve 7 represents the zero-level N—N of the stored liquid which is transferred to the right-hand leg of the U-pipe whence the respective hydrostatic pressures of the tank may be ascertained by means of the present measuring device. The outlet 5 also serves for letting off air-bubbles which might have collected in the liquid contained in the left-hand leg of the U-pipe; this outlet is closed and opened by the electrovalve 7. For obtaining greater accuracy of the zero-position to be transferred to the right-hand leg of the U-pipe the left-hand leg may have a somewhat greater diameter. Both legs preferably made of glass communicate with a duct 10 of the connecting body 9. Said duct 10 is provided with a cock 11 for filling the U-pipe with mercury or removing the mercury from it in order to clean both parts. The duct 10 communicates also with the displacing vessel 15 and may be disconnected therefrom by the cock 12 operated by hand.

The supply from the vessel 15 of the mercury required for adjusting the zero-position in the right-hand leg of the U-pipe is effected according to the invention by means of compressed air flowing from the container 20 through line 18 and the electrically controlled inlet valve 16 and forcing the mercury while cock 12 is open from the displacing vessel into the U-pipe 6 until it touches the stationary electrode 31, whereby as explained hereafter, in the same moment the valve 16 is shut off, the signal-lamp 33 flashes up and the acoustic signal 34 sounds so as to remind the operator to close cock 12 by hand. Subsequently, when another circuit including the electrovalve 17 is interrupted, the compressed air may escape from the displacing vessel 15 into the open air through said electrovalve 17, then open, as will be described hereinafter.

To the socket 8 on the right-hand leg 6 of the U-pipe is connected the compressed air line 19 communicating with the container 20, another branch leading to the exactly measuring gauge 28 communicating at its other end through line 29 and hand-operated cock 30 with the air-space of tank 1 to subtract at once any gas-pressure acting upon the liquid when reading off the hydrostatic pressure at the gauge 28. The compressed-air container 20 is pumped up by the hand pump 22 and is provided with a simple control-gauge 21 for indicating the required pressure. In the compressed-air line 19 an inlet valve 23 and an outlet valve 24 are provided

likewise actuated by electricity, valve 23 being, for instance, opened and valve 24 closed by the current. The object of the valve 24 is to let the compressed air escape from the line 19 only gradually so that the mercury in the right-hand leg of the U-pipe rises only slowly and the valve 24 is shut off precisely at the moment when the rising mercury-level touches the electrode 31. This circuit, of course, cannot be identical with the circuit by which the valve 24 previously was kept closed while the valve 23 was opened, as now valve 23 must also be closed so as to prevent the compressed air from entering line 19. The outlet valve 24 opens toward a container 27 provided with a throttling device 26 which is intended to deaden and to avoid as far as possible the oscillations of the gradually escaping mass of air, whereas the escape of the compressed air is to be retarded by the throttling in order to obtain a calm and slow rising of the mercury. An electric outlet valve 25 is further attached to the air container 27 which remains closed during the measuring operation, i. e. while the compressed air gradually escapes through valve 24, and is only opened after the measuring has been finished in order to rapidly remove the compressed air out of the line 19.

The signal lamp 33 is connected in such a way that it flashes up at each contact of the meniscus of the mercury with the point of the electrode 31, that is at each occurrence of the zero-position, due to the circuit closed hereby, whereas the lamp is extinguished when this circuit is interrupted by the falling mercury leaving the electrode. A sound signal 34 is included in the circuit containing the signal lamp 33 and the electrode 31, if the cock 12 is in open position. As soon as the rising mercury contacts the electrode 31, said sound signal 34 is rendered operative and remains in operative condition until the cock 12 is closed and the circuit is interrupted. For this purpose the cock 12 is provided with a contact 13 which is in engagement with the contact 14 of the circuit of the signal-lamp 33 and the acoustic signal 34 when the cock is opened, and which contact 13 is disengaged from the contact 14 of said circuit when the cock is closed, so as to interrupt said circuit.

The electric current for the different circuits 50 is supplied by a storage battery 35 A and B, whereas by connecting the switch 36 with the different knobs, for instance, a, b, c, the circuits required for the automatic adjustment of the zero-positions for the zero-level N—N and the full hydrostatic pressure are connected or disconnected. The terminals for connecting all electrovalves 4, 7, 16, 17, 23, 24, 25, the signal lamp 33, the switch 36 and all other parts of the measuring device to be connected with the circuits are denoted by 37. The electrovalves 4, 7 and 23 are closed when not energized and are open when energized while the electrovalves 16, 17, 24 and 25 are closed when under current and are open when not energized. In order to avoid the formation of sparks at the contacts, a corresponding number of condensers may be inserted into the electric lines. The storage battery consists of two separate parts 35A and 35B enclosed in a common box, each part having independent terminals.

The measuring device may be operated as follows:

First connection.—The valve 3 is opened 75 slightly by hand so as to fill the left-hand leg

6 of the U-pipe with liquid discharged from the tank 4.

The compressed-air container 29 is filled with compressed air by means of the pump 22.

The cock 12 is opened manually by rotating same through 90° from the position shown in the figure, whereby the contact 13 is brought into engagement with contact 14. At the same time the change-over switch 36 is put on contact *a*. Thus, the circuit I (denoted by a full line) is closed, said circuit I comprising switch 36—valves 17, 7, 4—electrode 32—mercury in the U-pipe 6, 6—part 35A of the battery—switch 36.

Valves 4, 7, being in said circuit I and being energized are open, valve 17, being likewise in said circuit I and being energized is closed.

Valve 16 being not in said circuit I and being not energized is open.

The valve 3 may now be closed.

Compressed air is introduced into the displacing vessel 15 through the open valve 16. Under the influence of the air-pressure the mercury columns in both legs 6 of the U-pipe rise; excess liquid in the left leg of the U-pipe may escape through the outlet 5 of the open valve 7.

The upper edge of the outlet 5 is located in the same horizontal plane as the zero-level (line N—N) of the liquid in the tank 4.

As soon as the meniscus of the mercury touches the electrode 31, the circuit II (denoted by short dashes ----) is closed, said circuit II comprising mercury column—electrode 31—electric signal—lamp 33—valve 16—battery 35B—acoustic signal 34—contacts 14 and 13—body 9—mercury column.

The contact between the mercury and the electrode 31 causes the valve 16 to close, the optic signal (lamp 33) to flash up and the acoustic signal 34 to ring. As soon as the cock 12 is closed by hand, the circuit II is interrupted so that the signal-lamp 33 and the signal bell 34 are turned off.

If contact between the mercury meniscus and the point of the electrode 31 is established, the difference between the levels of the mercury in both legs 6 equals the hydrostatic pressure of the gasoline or other liquid in the left-hand leg up to the outlet 5, corresponding to the zero-position N—N in the tank 4. Thus, the first operation, i. e. the zero adjustment in the U-pipe, is completed.

Second connection.—The valve 3 is opened by hand and at the same time the change-over switch 36 is brought into its next position, i. e. the switch is put on contact *b*, whereby the circuit III (denoted by dash and dot lines -----) is closed, said circuit III comprising the valves 23, 24, 25 and 4, the contact 32, mercury in the U-pipe 6, 6, body 9, battery 35A and switch 36. Valves 4 and 23 thus being energized are opened while the energized valves 24 and 25 are closed.

Now the compressed air flows from the container 20 through the pipe 19 into the right-hand leg of the U-pipe. Valve 17 being not energized after interruption of the circuit I by switch 36 is open, whereas valve 7, likewise not energized, is closed. Now the mercury in the right-hand leg of the U-pipe is exposed to the pressure of the compressed air acting against the full pressure of the liquid of the tank which in turn acts on the mercury in the left-hand leg of the U-pipe.

The supply of compressed air continues until the level of the mercury in the right-hand leg of the U-pipe depressed by the pressure of the

compressed air falls slightly below the point of the electrode 31 and becomes disengaged from the latter. Valve 23 is open because circuit III is still closed.

5 The cross-sections of the openings of valve 23 and valve 16 are chosen in such a manner that the main part of the compressed air enters the right-hand leg of the U-pipe and that only a small part of the compressed air may escape 10 through the valves 16 and 17 into the open air.

The pressure of the air in the right-hand leg of the U-pipe is now higher than the pressure of the liquid in the tank. The switch 36 is now brought into its next position.

15 *Third connection.*—The changeover switch 36 is put on contact *c*. The circuit IV (denoted by long dashes -----) comprises the battery 35A, the contact *c* of the switch 36, the valve 24, the signal lamp 33, the electrode 31, the mercury in the right-hand leg of the U-pipe, the body 9 and the battery 35A. However, as at this time the mercury is somewhat below the electrode 31 in the right-hand leg of the U-pipe 6, the circuit IV is interrupted at the electrode 31 and, 20 consequently, the valve 24 is not energized and therefore open.

The valves 25 and 4 in parallel to circuit IV (also denoted by long dashes -----), however, are energized and, therefore, valve 25 is closed 30 and valve 4 is open.

The valve 23 being in circuit III now interrupted by the switch 36 is not energized and, therefore, is closed.

35 The compressed air escapes from the right-hand leg of the U-pipe through valve 24 and escapes through the throttling device 26 into the open air.

The manually adjustable throttling device 26 permits the control of the rate of flow of the air escaping from the right-hand leg of the U-pipe during the measurement, so that a calm and slow rising of the mercury may be obtained. Such an adjustment of the throttling device 26, is effected 40 once, may be used for a great number of measurements.

45 Owing to the reduction of the pressure caused by the escape of air through the throttling device 26, the mercury rises in the right-hand leg of the U-pipe. As soon as the mercury touches the point of electrode 31 the circuit IV is closed. The signal lamp flashes up again and the valve 24 is closed.

The meniscus of the mercury is now again at the level which corresponds to the zero-position (N—N) in the tank 4, but this time it is exposed 50 to pressure of the liquid in the tank and the compressed air. Therefore the full pressure of the liquid in the tank now balances the pressure of the compressed air.

55 60 This pressure of the liquid in the tank which exactly equals the pressure of the compressed air may be read off from the gauge 28 the left leg of which is connected to the compressed air line 19. Now, the measurement of the pressure of the liquid in the tank is completed.

65 The pressure indicated by the gauge multiplied with a conversion factor and multiplied with the bottom surface of the tank reveals the weight of the liquid in the tank above the zero position N—N.

70 75 If gases have formed above the liquid in the tank (for instance, in closed gasoline tanks) the cock 30 is opened by hand before the measurement, so that the gas pressure is transmitted through line 29 to the right-hand leg of the

gauge 28 and the gauge again indicates the exact pressure of the liquid in the tank.

The circuit of the valve 4 is further connected to the contact 32 in the left-hand leg of the U-pipe. When the pressure in said left-hand leg surpasses a certain value, for instance when an insufficient quantity of compressed air is supplied to the right-hand leg of the U-pipe, the mercury in said right-hand leg excessively rises and may under certain conditions enter the air line 19.

The safety contact 32 arranged in the left-hand leg of the U-pipe prevents the mercury from an undesired excessive rising in the right-hand leg of the U-pipe. As soon as the mercury in the left-hand leg falls below the contact point 32, the circuit of the valve 4 is interrupted, whereby the valve 4 is closed and the supply of the liquid from the tank 1 to the U-pipe is stopped.

Of course, the invention is not limited to the modification shown and described in the present specification, but includes all other modifications in which the zero-adjustment device provided at the U-pipe is automatically adjusted for the zero-level N—N of the tank as well as for its full hydrostatic pressure which may be effected, for instance, by means of one single switch 36 as shown or, if desired, in another way.

While the liquid conductor in the U-pipe 6 is described as being mercury, it may consist of any other suitable liquid not miscible with the liquid in the tank 1 and being a conductor of electricity, such as an aqueous solution of sodium sulfate. In this case alternating current may be used for actuating the valves to avoid the development of gases.

I claim:

1. In an apparatus for ascertaining the hydrostatic pressure of the liquid in a container the combination of a U-shaped pipe having a first and a second leg and having a bow connecting said legs, said U-pipe containing a liquid not miscible with the liquid in the container and being a conductor of electricity, the first leg of which pipe communicates with the liquid in the container near the bottom of the latter, a vessel, a source of compressed air, a first line connecting said source of compressed air with said vessel, a second line connecting said source of compressed air with the second leg of the U-pipe, said vessel communicating with the bow of the said U-shaped pipe and filled with the same liquid conductor as the latter, a pressure gauge attached to the said second line, electrovalves arranged firstly between the container and said first leg of the U-pipe, secondly between the said vessel and the source of compressed air, and thirdly between the said second line and the source of compressed air, electrically controlled outlet valves on the first leg, on the vessel and on the said second line, a hand-controlled cock between the bow of the U-pipe and the vessel, an electrode in said second leg of the U-pipe, an optic signal to be operated by the contact of the electrode with the liquid conductor, an acoustic signal to be operated by said hand controlled cock and a single switch adapted to selectively connect the said valves with a source of electricity.

2. In an apparatus for ascertaining the hydrostatic pressure of the liquid in a container the combination of a U-shaped pipe having a first and a second leg and having a bow connecting said legs, said U-pipe containing a liquid not miscible with the liquid in the container and be-

ing a conductor of electricity, the first leg of which pipe communicates with the liquid in the container near the bottom of the latter, a vessel, a source of compressed air, a first line connecting said source of compressed air with said vessel, a second line connecting said source of compressed air with the second leg of the U-pipe, said vessel communicating with the bow of the said U-shaped pipe and filled with the same liquid conductor as the latter, a pressure gauge attached to the said second line, electro-valves arranged firstly between the container and said first leg of the U-pipe, secondly in said first line between the said vessel and the source of compressed air, and thirdly between the said second line and the source of compressed air, electrically controlled outlet valves on the first leg, on the vessel and on the said second line, a hand-controlled cock between the bow of the U-pipe and the vessel, an electrode in the second leg of the U-pipe, an optic signal to be operated by the contact of the electrode with the liquid conductor, an acoustic signal to be operated by said hand-controlled cock and a switch adapted to establish one circuit over the electrovalve opening under current located between the container and the first leg of the U-pipe and said valve connecting the liquid in the first leg of the U-pipe with the open air, a first battery, a second battery, the valve between the source of compressed-air and the vessel being open if not energized, the outlet valve on the vessel being closed under current—whereby the liquid conductor in the second leg of the U-pipe is raised and a circuit is shunted over the liquid conductor, the electrode in the second leg of the U-pipe, the optic signal, the valve in said first line, said second battery and back to the liquid conductor, another circuit over the first battery, the valve between the container and said first leg of the U-pipe, a second outlet valve of the compressed-air line, said first outlet valve of the compressed air line, the valve between the compressed-air line and the source of compressed air—whereby the shunt circuit is interrupted and the full hydrostatic pressure in the container is made to act on the liquid conductor in the first leg of the U-pipe and the full air pressure is allowed to act on the liquid conductor in the second leg of the U-pipe, so as to separate the liquid conductor from the electrode in this leg until the circuit is broken by the next actuation of the switch and thereby the valve between the compressed air line and the source of compressed air is closed and the first outlet valve on the compressed air line is opened and a third circuit over the first-named battery, the valve between the container and said first leg of the U-pipe, and the second outlet valve of the compressed-air line—whereby the full hydrostatic pressure is balanced with the pressure in the compressed-air line connecting the second leg of the U-pipe with the pressure gauge.

3. In an apparatus for ascertaining the hydrostatic pressure of a liquid in a tank, the combination of: a U-pipe having a first and a second leg and having a bow connecting said legs, said U-pipe containing an electro-conductive liquid not miscible with the liquid of the tank, the first leg of said U-pipe communicating with said tank near the bottom thereof, a pressure gauge, a first line connecting said pressure gauge with the interior of the second leg of said U-pipe, a vessel, a second line connecting the bow of said U-pipe with said vessel, a hand-operated cock

arranged in said second line, said cock being settable in an open position wherein said vessel communicates with the bow of said U-pipe and being settable in a closing position wherein said vessel is disconnected from said U-pipe, a source of compressed air, a third line connecting said source of compressed air with said vessel, a first electrovalve in said third line for opening and closing same, a second electrovalve connected with said vessel for connecting same with the open air in open position and for closing same in closing position, an electric source, automatic electric means responsive to the rising of the liquid in said second leg of the U-pipe beyond a predetermined level for connecting said first electrovalve with said electric source so as to bring same into closing position, and a switch for connecting said second electrovalve with said electric source so as to bring same into closing position and for disconnecting said second electrovalve from said electric source so as to bring same into open position.

4. In an apparatus for ascertaining the hydrostatic pressure of a liquid in a tank, the combination of: a U-pipe having a first and a second leg and having a bow connecting said legs, said U-pipe containing an electroconductive liquid not miscible with the liquid of the tank, the first leg of said U-pipe communicating with said tank near the bottom thereof, a pressure gauge, a first line connecting said pressure gauge with the interior of the second leg of said U-pipe, a vessel, a second line connecting the bow of said U-pipe with said vessel, a hand-operated cock in said second line, said cock being settable in an open position wherein said vessel communicates with the bow of said U-pipe and being settable in a closing position wherein said vessel is disconnected from said U-pipe, a source of compressed air, a third line connecting said source of compressed air with said vessel, a fourth line connecting said source of compressed air with said first line, a first electrovalve in said third line for opening and closing same, a second electrovalve in said fourth line for opening and closing same, a first electrically controlled outlet valve connected with said vessel, a second electrically controlled outlet valve connected with said first line, a third electrically controlled outlet valve connected with said first leg of the U-pipe, an electric source, automatic electric means responsive to the rising of the liquid in said second leg of the U-pipe beyond a predetermined level for connecting said first electrovalve with said electric source so as to energize said electrovalve for closing said third line, said second electrovalve and said electrically controlled outlet valves being in electrical connections with said electric source, and a change-over switch in said electrical connections for selectively energizing and de-energizing said second electrovalve and said electrically controlled outlet valves.

5. In an apparatus as claimed in claim 4, said first leg of the U-pipe communicating with said tank through a fifth line, a third electrovalve in said fifth line for opening and closing same, said third electrovalve being in electrical connection with said electric source and being open when energized, and automatic electrical safety means responsive to the falling of the liquid in the first leg below a predetermined level for disconnecting said third electrovalve from said electric source so as to de-energize said electrovalve for closing said fifth line.

6. In an apparatus as claimed in claim 4, said automatic electric means including an electrode arranged in said second leg of the U-pipe for contact with the liquid therein when the liquid rises beyond a predetermined level, a switch connected with said cock, said switch being automatically closed when the cock is opened and being automatically opened when the cock is closed, and at least one electric signal, said 10 first electrovalve, said electric source, said cock-controlled switch, the liquid of the U-pipe, said electrode, and said electric signal constituting a circuit.
7. In an apparatus as claimed in claim 4, said 15 automatic electric means including an electrode arranged in said second leg of the U-pipe for contact with the liquid therein when the liquid rises beyond a predetermined level, a switch connected with said cock, said switch being automatically closed when the cock is opened and being automatically opened when the cock is closed; an optical signal; an acoustical signal; said first electrovalve, said first outlet valve and said second outlet valve being open when de-energized and being closed when energized; said 20 second electrovalve and said third outlet valve being closed when de-energized and being open when energized; said change-over switch including a first, a second and a third set of terminals and a contacting element cooperating with said terminals; a first circuit including said electric source, the first set of terminals of said change-over switch, said first outlet valve and said third outlet valve; a second circuit including said electric source, said first electrovalve, said optical signal, said electrode, the liquid of the U-pipe, said cock-operated switch and said acoustical signal, said acoustical signal being arranged between said switch and said electric source, said optical signal being arranged between said first electrovalve and said electrode; a third circuit including said electric source, the second set of terminals of said change-over switch, said second electrovalve and said second 25 outlet valve; and a fourth circuit including said electric source, the third set of terminals of said change-over switch, said second outlet valve, said optical signal, said electrode and the liquid of the U-pipe.
8. In an apparatus as claimed in claim 4, said first leg of the U-pipe communicating with said tank through a fifth line, a third electrovalve in said fifth line for opening and closing same, said automatic electric means including a first electrode arranged in said second leg of the U-pipe for contact with the liquid therein when the liquid rises beyond a predetermined level; a second electrode arranged in said first leg of the U-pipe for disengagement from the liquid therein when the liquid falls below a predetermined level; a switch connected with said cock; said switch being automatically closed when the cock is opened and being automatically opened when the cock is closed; an optical signal; an acoustical signal; said first electrovalve, said first outlet valve and said second outlet valve being open when de-energized and being closed when energized, said second electrovalve, said third outlet valve and said third electrovalve being closed when de-energized and being open when energized; said change-over switch including a first, a second and a third set of terminals and a contacting element cooperating with said terminals; a first circuit including said electric source, the first set of terminals of said change-over switch, 30
- 35
- 40
- 45
- 50
- 55
- 60
- 65
- 70
- 75

said first outlet valve, said third outlet valve and said third electrovalve; a second circuit including said electric source, said first electrovalve, said optical signal, said first electrode, the liquid of the U-pipe, said cock-operated switch and said acoustical signal, said acoustical signal being arranged between said switch and said electric source, said optical signal being arranged between said first electrovalve and said first electrode; a third circuit including said electric source, the second set of terminals of said change-over switch, said second electrovalve, said second outlet valve and said third electrovalve; a fourth circuit including said electric source, the third set of terminals of said change-over switch, said second outlet valve, said optical signal, said first electrode and the liquid of the U-pipe, said third electrovalve being connected in parallel to said fourth circuit; and a fifth circuit including said electric source, said third electrovalve, said second electrode and the liquid of the U-pipe.

9. In an apparatus as claimed in claim 4, said first leg of the U-pipe communicating with said tank through a fifth line, a third electrovalve in said fifth line for opening and closing same, said automatic electric means including a first electrode arranged in said second leg of the U-pipe for contact with the liquid therein when the liquid rises beyond a predetermined level; a second electrode arranged in said first leg of the U-pipe for disengagement from the liquid therein when the liquid falls below a predetermined level; a switch connected with said cock; said switch being automatically closed when the cock is opened and being automatically opened when the cock is closed; an optical signal; an acoustical signal; said first electrovalve, said first outlet valve and said second valve being open when deenergized and being closed when energized; said second electrovalve, said third outlet valve and said third electrovalve being closed when de-energized and being open when energized; said change-over switch including a first, a second and a third set of terminals and a contacting element cooperating with said terminals; a first circuit including said electric source, the first set of terminals of said change-over switch, said first outlet valve, said third outlet valve, said third electrovalve, said second electrode and the liquid of the U-pipe; a second circuit including said electric source, said first electrovalve, said optical signal, said first electrode, the liquid of the U-pipe, said cock-operated switch and said acoustical signal, said acoustical signal being arranged between said switch and said electric source, said optical signal being arranged between said first electrovalve and said second electrode; a third circuit including said electric source, the second set of terminals of said change-over switch, said second electrovalve, said second outlet valve, said fourth outlet valve, said third electrovalve, said second electrode and the liquid of the U-pipe; a fourth circuit including said electric source, the third set of terminals of said change-over switch, said second outlet valve, said optical signal, said first electrode and the liquid of the U-pipe; and a fifth circuit comprising said fourth outlet valve, said third electrovalve and said second electrode, said fifth circuit being connected in parallel to said second outlet valve and said first electrode of said fourth circuit.

10. In an apparatus as claimed in claim 4, said first leg of the U-pipe communicating with said tank through a fifth line, a third electrovalve in said fifth line for opening and closing same, a container, a throttling outlet on said container, a fourth electrically controlled outlet valve on said container, said second outlet valve communicating with said container, said automatic electric means including a first electrode arranged in said second leg of the U-pipe for contact with the liquid therein when the liquid rises beyond a predetermined level; a second electrode arranged in said first leg of the U-pipe for disengagement from the liquid therein when the liquid falls beyond a predetermined level; a switch connected with said cock; said switch being automatically closed when the cock is opened and being automatically opened when the cock is closed; an optical signal; and acoustical signal; said first electrovalve, said first outlet valve, said second outlet valve and said fourth outlet valve being open when de-energized and being closed when energized; said second electrovalve, said third outlet valve and said third electrovalve being closed when de-energized and being open when energized; said change-over switch including a first, a second and a third set of terminals and a contacting element cooperating with said terminals; a first circuit including said electric source, the first set of terminals of said change-over switch, said first outlet valve, said third outlet valve, said third electrovalve, said second electrode and the liquid of the U-pipe; a second circuit including said electric source, said first electrovalve, said optical signal, said first electrode, the liquid of the U-pipe, said cock-operated switch and said acoustical signal, said acoustical signal being arranged between said switch and said electric source, said optical signal being arranged between said first electrovalve and said second electrode; a third circuit including said electric source, the second set of terminals of said change-over switch, said second electrovalve, said second outlet valve, said fourth outlet valve, said third electrovalve, said second electrode and the liquid of the U-pipe; a fourth circuit including said electric source, the third set of terminals of said change-over switch, said second outlet valve, said optical signal, said first electrode and the liquid of the U-pipe; and a fifth circuit comprising said fourth outlet valve, said third electrovalve and said second electrode, said fifth circuit being connected in parallel to said second outlet valve and said first electrode of said fourth circuit.

55 GEORG SARUCHANOFF.
